US0D1072282S

(12) **United States Design Patent** (10) **Patent No.:** **US D1,072,282 S**
(45) **Date of Patent:** **** Apr. 22, 2025**

(54) **TOP CAP FOR A LADDER**

- (71) Applicant: **LITTLE GIANT LADDER SYSTEMS, LLC**, Springville, UT (US)
- (72) Inventors: **B. Scott Maxfield**, Mapleton, UT (US); **N. Ryan Moss**, Mapleton, UT (US); **Brian B. Russell**, Saratoga Springs, UT (US)

(**) Term: **15 Years**

(21) Appl. No.: **29/827,612**

(22) Filed: **Feb. 21, 2022**

Related U.S. Application Data

- (60) Continuation of application No. 29/771,366, filed on Feb. 22, 2021, now Pat. No. Des. 944,417, which is a division of application No. 29/679,726, filed on Feb. 8, 2019, now Pat. No. Des. 911,555.
- (51) **LOC (15) Cl.** **25-04**
- (52) **U.S. Cl.** **D25/68**

(57) **CLAIM**

The ornamental design for a top cap for a ladder as shown and described.

DESCRIPTION

FIG. 1 is a front perspective view of a top cap for a ladder showing our new design;

FIG. 2 is a rear perspective view of the top cap for a ladder shown in FIG. 1;

FIG. 3 is a front view of the top cap for a ladder shown in FIG. 1;

FIG. 4 is a rear view of the top cap for a ladder shown in FIG. 1;

FIG. 5 is a right side view of the top cap for a ladder shown in FIG. 1;

FIG. 6 is a left side view of the top cap for a ladder shown in FIG. 1;

FIG. 7 is a top view of the top cap shown in FIGS. 1; and, FIG. 8 is a bottom view of the top cap for a ladder shown in FIG. 1.

Broken lines shown immediately adjacent the shaded areas represent bounds of the claimed design. All other broken lines are shown for the purpose of illustrating environmental boundaries. The broken lines form no part of the claimed design.

1 Claim, 7 Drawing Sheets
